[57] ABSTRACT

A cartridge fuse having an open ended sleeve type tubular body member with a removable terminal disc type plate disposed at each end thereof and supporting therebetween a replaceable solid fusible electrical conductive link adapted to melt at a given temperature to break an electrical circuit, the terminal plate being removably secured to the body member by a terminal cap threaded onto each end of the body member, and the body member being manufactured of a transparent polysulfone material having a dielectric constant of 3.14 at 60 Hertz, this providing a view of the internal fusible link from any angle through the body.

3 Claims, 3 Drawing Figures

CARTRIDGE FUSE

BACKGROUND OF THE INVENTION

1. Field of the Invention

This invention relates generally to cartridge fuses and more particularly to a novel and improved cartridge fuse having a replaceable fusible link therein which melts when overheated to break an electrical circuit and wherein the link is visible through a transparent body member for inspection thereof exteriorly of the fuse.

2. Description of the Prior Art

It has been known in the prior art to provide cartridge fuses of various sizes, capacities, and configurations, but all of such fuses suffer from the disadvantage of an individual having to shake or otherwise handle or test the same to determine the working operation thereof, with the individual not being able to determine the actual condition of the fuse link inside the fuse to see if it has been partially damaged due to electrical overloads or the like during the use of the fuse and should thus be replaced to assure maximum fuse capacity. Among such prior art devices are those of the type generally illustrated in the U.S. patents of Sherwood No. 3,365,559; Baumbach No. 3,377,448; Baird No. 3,601,737; and Kozacka No. 3,529,270.

SUMMARY OF THE INVENTION

The present invention recognizes the deficiencies and disadvantages of presently available cartridge fuses and provides a novel solution thereto in the form of an improved cartridge fuse having a transparent tubular body member manufactured of polysulfone material providing required insulating characteristics and providing for clear visibility of the condition of the fuse link at all times both during storage and during actual electrical operation of the cartridge fuse.

It is a feature of the present invention to provide an improved cartridge fuse which is relatively simple in its construction and which therefore may be readily manufactured at a relatively low cost and by simple manufacturing methods.

A further feature of the present invention provides an improved cartridge fuse which is possessed of few parts which are of a rugged and durable construction and which therefore may be guaranteed by the manufacturer to withstand many years of intended usage providing for the replacement of the fuse link in the fuse whenever required as determined by a visible inspection thereof through the transparent walls of the body member or by a break in the electrical circuit to which the fuse is connected in series relationship.

Yet still a further feature of the present invention provides a cartridge fuse adapted to readily replace cartridge fuses presently available to provide for an improved cartridge fuse to update equipment and the like.

Yet still a further feature of the present invention provides an improved cartridge fuse which is easy to use and reliable and efficient in operation.

Other features and advantages of this invention will be apparent during the course of the following description.

Brief Description of the Drawings

In the accompanying drawings forming a part of this specification, and in which like reference characters are employed to designate like parts throughout the same:

FIG. 1 is a perspective view of the cartridge fuse of the present invention;

FIG. 2 is an exploded perspective view of the cartridge fuse of the invention; and

FIG. 3 is a front elevational view of the cartridge fuse of the invention.

Description of the Preferred Embodiment

15 Referring now to the drawings in detail there is illustrated a preferred form of a cartridge fuse constructed in accordance with the principles of the present invention and designated generally in its entirety by the reference numeral 10 and which is comprised of a body member 11, a pair of terminal plates 12, a replaceable solid fusible electrical conductive link 13, and a pair of terminal end caps 14.

The body member 11 is manufactured of an open ended sleeve type tubular housing 21 having threads 22 disposed circumferentially about the opposite end thereof. The housing 21 is transparent and is manufactured of a polysulfone material having a dielectric constant of 3.14 at 60 Hertz, this providing a novel use for this material as to having the desired optical characteristics to provide complete visibility therethrough in a manner to determine the condition of fuse link 13 at any time during actual operation of the fuse 10, this material being non-breakable as compared to the use of glass tubes and the like. This is a novel use of polysulfone material which is manufactured by Union Carbide Company as attested to by an investigation conducted by Underwriters Laboratories, Inc. under File No. E43933 at which time this material was approved for use in the renewable cartridge fuse of the present invention.

20 30 35 40 45 50 The terminal plates 12 are each of an identical construction and are of substantially flat disc shapes having a diameter greater than the internal diameter of the sleeve 11 but less than the external diameter thereof so as to be engaged on opposite ends 23 and 24 of the body member, each of the plates provided with a slot 26 adapted to receive opposite ends 31 of fuse link 13 therethrough which are then bent in an angle of approximately 90° to overlie the outer surface of the associated terminal plate.

55 60 65 The fusible electrical conductive link 13 is adapted to melt at a given temperature to break an electrical circuit with such design characteristics thereof selected for the capacity of the circuit to be protected as normally measured in amperes, the normal type of link being as illustrated in the drawings and including a reduced cross-sectional area 32 which normally will vary depending upon the rating of the fuse link.

The terminal end caps 14 are each identical in construction and are of a cylindrical configuration having side walls 41 and a back surface 42 with an open front end 43 with there being an interior threaded bore 44 opening out of the front end and adapted to be threadedly received on body member threads 22 in a manner to capture an associated one of terminal plates 12 intermediate an associated end 23, 24 of the body member and an interior surface of the terminal cap back end 42. The terminal caps are of an electrically conductive

metal material as are the terminal plates 12 and thus provide terminals exterior of the body member for electrically connecting the fuse link 13 in series relationship with an electrical circuit to be protected, this normally being accomplished by inserting the fuse 10 between a pair of fuse holders 45 (FIG. 3) which electrically contacts the terminal caps 14.

There is thus provided a novel use for the polysulfone material to provide for a transparent housing of a renewable cartridge fuse in order to provide for visibility of the fuse link interior of the body member at any time desired by an individual without having to remove the fuse from the circuit or having to de-energize the circuit which the fuse is protecting. In this manner the condition of the fuse link may be readily inspected at normal intervals and be replaced if such inspection illustrates any damage or disfiguration thereto such as may be encountered due to brief overloads in the circuit and the like which are not sufficient to melt the fuse link and break the electrical circuit but which are sufficient to partially melt or damage the fuse link and thus affect its efficiency of operation.

It is to be understood that the form of this invention herewith shown and described is to be taken as a preferred example of the same, and that this invention is not to be limited to the exact arrangement of parts shown in the accompanying drawings or described in this specification as various changes in the details of construction as to shape, size, and arrangement of parts may be resorted to without departing from the spirit of the invention, the scope of the novel concepts thereof, or the scope of the subjoined claims.

Having thus described the invention, what is claimed is:

1. A renewable cartridge link fuse comprising: an open ended sleeve type substantially tubular body member of transparent polysulfone material pro-

viding unobscured visibility therethrough; a pair of substantially flat disc shaped terminal plate members each having a slotted opening provided therein, each plate member having a diameter greater than the interior diameter of said body member and less than the exterior diameter of said body member, each plate member adapted to restingly engage an associated end of said body member concentric with the axis of said body member; a solid fusible electrical conductive link element adapted to melt at a given temperature, each end of said link adapted to pass through an associated slotted opening of an associated plate member and then be bent at an angle of about ninety degrees to overlie the exterior surface of said plate member; and

a pair of external electrical circuit connection means, each of said means adapted to be mounted to an associated end of said body member and electrically connect to said fusible link providing a series electrical circuit through said fusible link element.

2. The renewable cartridge fuse as set forth in claim 1 wherein said polysulfone material has a dielectric constant of 3.14 at 60 Hertz.

3. The renewable cartridge fuse as set forth in claim 2 wherein said body member is threaded at the opposite ends thereof about its exterior circumference, and wherein said external electrical circuit connection means comprises cylindrical terminal end caps, each end cap having cylindrical side walls, a closed back end, and an open front end, the interior circumference of each of said end caps being threaded and adapted to threadedly engage associated ends of said body member to secure said end caps thereto in a manner removably retaining said terminal plate to said body manner.
